Joseph Becvar, Wickliffe, Ohio, assignor to The Cleveland Cooperative Stove Company, Cleveland, Ohio, a corporation of Ohio

Application November 14, 1935, Serial No. 59,567

Term of patent 3½ years

To all whom it may concern:

Be it known that I, Joseph Becvar, a citizen of the United States, residing at Wickliffe, in the county of Lake and State of Ohio, have invented a new, original, and ornamental Design for a Combined Back Splash Panel and Lighting Unit for Cooking Ranges, of which the following is a specification, reference being had to the accompanying drawing, forming part thereof.

Fig. 1 is a front elevational view of a combined back splash panel and lighting unit for cooking ranges.

Fig. 2 is a side view thereof.

I claim:

The ornamental design for a combined back splash panel and lighting unit for cooking ranges as shown.
